UNITED STATES PATENT OFFICE.

LEONARD B. BROOKS, OF INDEPENDENCE, IOWA.

WASHING-MACHINE.

SPECIFICATION forming part of Letters Patent No. 702,535, dated June 17, 1902.

Application filed February 26, 1902. Serial No. 95,768. (No model.)

To all whom it may concern:

Be it known that I, LEONARD B. BROOKS, a citizen of the United States, residing at Independence, in the county of Buchanan and State of Iowa, have invented a new and useful Washing-Machine, of which the following is a specification.

The invention relates to improvements in washing-machines.

10 The object of the present invention is to improve the construction of washing-machines and to provide an exceedingly simple and inexpensive one capable of being readily mounted on and removed from a tub or other receptacle and adapted to be rapidly and conveniently operated, whereby clothes are quickly and thoroughly washed.

20 The invention consists in the construction and novel combination and arrangement of parts hereinafter fully described, illustrated in the accompanying drawings, and pointed out in the claim hereto appended.

In the drawings, Figure 1 is a perspective view of a washing-machine constructed in accordance with this invention and shown applied to a tub. Fig. 2 is an enlarged vertical sectional view of the washing-machine. Fig. 3 is a detail sectional view illustrating the manner of connecting the vertically-movable 30 pounder with the operating-lever and the oscillating bar.

Like numerals of reference designate corresponding parts in all the figures of the drawings.

35 1 designates a vertically-movable clothes-pounder designed to be constructed in any preferred manner and provided at the top with a socket for the reception of a stem 2, which is adjustably secured within a clamp 3, and the said pounder is adapted to force air and water through the clothes, whereby the dirt is removed therefrom. The clothes-pounder preferably consists of a conical shell, an inner vertical tube 4, and a diaphragm 5, arranged near the lower end of the tube and provided with flanges 6, forming pockets. The tube, which extends to within a short distance of the lower edge of the conical shell, is provided at its top with openings 45 50 communicating with the exterior of the shell and covered by semitubular guards or hooks

7, which prevent the water from splashing on the operator.

The clamp 3, which is vertically arranged, is tubular to receive the rounded stem, and it 55 is provided with a clamping-screw 8 and has openings or cut-away portions above and below the same. The central portion of the outer side of the clamp is provided with a boss or enlargement arranged around the perforation for the clamping-screw. The stem of the pounder is constructed of wood and is provided with a metal plate 9, arranged to be engaged by the clamping-screw to enable the pounder to be securely clamped at any desired adjustment without injuring the stem. The ends of the clamp are provided with lugs or enlargements 10, forming flat faces and perforated for the reception of upper and lower pivots 11 and 12, which connect the 70 clamp with an oscillating bar and with an operating-lever 14, the bar and the lever being arranged parallel with each other and adapted to oscillate in unison to move the pounder vertically. The pivots are connected at the 75 threaded ends by a vertical plate or bar 15, which forms a brace. The pivots 11 and 12 preferably consist of bolts having threaded outer ends and having their inner ends or heads countersunk in the upper and lower 80 ends of the clamp, at the lugs or enlargements 10 thereof. The outer threaded ends of the pivots are provided with nuts, as clearly shown in Fig. 3 of the drawings.

The inner ends of the bar 13 and the lever 85 14 are pivoted by bolts 16 and 17 to the upper and lower ends of an upright clip 18, which is approximately U-shaped in cross-section and which is mounted on one of the sides or legs of a U-shaped support 19. The 90 leg 20 of the U-shaped support 19 is provided with flanges or collars 21 and 22, arranged above and below the clip 18 and adapted to hold the latter against vertical movement, and the sides of the clip are extended at the 95 top and bottom to form perforated ears for the reception of the pivots 16 and 17. The clip is adapted to rotate on the arm or side of the support to enable the pounder to be arranged over different portions of the tub, 100 and the other side 24 of the U-shaped support is journaled or pivotally mounted, as

hereinafter explained, to coöperate with the clip to enable the pounder to be placed over any portion of the bottom of the tub or receptacle. The outer portion of the lever is shaped into a suitable handle or grip, and after the lever has been swung downward it is automatically raised by a contractile spring 25, located between the bar and the lever and secured at its inner or rear end to the bar at a point adjacent to the clip and at its outer end to the lever at a point beyond the clamp. When the lever is swung downward, the spring is distended and operates to raise the pounder when the pressure on the same is removed. By this construction the pounder is adapted to be rapidly operated to enable clothes and other fabrics to be quickly washed.

The rear side or leg of the U-shaped support is provided with a pair of horizontally-disposed bearing-plates 26 and 27, having inner and outer openings and fixed to the support, which is arranged in the inner openings. The outer bearing-openings 28 and 29 are arranged on a vertical pintle-rod 30, having upper and lower bearing portions and provided with upper and lower threaded ends 31 and 32. The upper end receives a nut 33, and the lower end is secured within a threaded socket 34 of an inverted-U-shaped clamp 35. The smooth bearing portions of the pintle-rod enable the bearing-plates to swing freely, and the nut effectually prevents the support from becoming disengaged from the pintle-rod when heavy pressure is applied to the operating-lever.

The inverted-U-shaped clamp, which is adapted to receive the upper edge of a tub or other receptacle, is provided at its outer side or jaw with a pair of clamping-screws,

and it is capable of enabling the washing-machine to be firmly and quickly mounted on a tub or other receptacle and of permitting the said washing mechanism to be readily removed.

What I claim is—

In a washing-machine, the combination of a clamp provided with means for engaging the upper portion of a tub and having an upwardly-extending threaded socket, an upright pintle-rod provided with threaded ends, the lower end being arranged within the threaded socket of the clamp and rigidly connected therewith, the approximately U-shaped support provided at its rear leg with upper and lower bearing-plates having inner and outer openings and arranged adjacent to the upper and lower ends of the pintle-rod and receiving the latter in the outer openings, the rear leg of the support being arranged in the inner openings and the bearing-plates being fixed to the said leg, a nut arranged on the upper end of the pintle-rod and engaging the upper bearing-plate, a clip mounted on the front leg of the support, an operating-lever fulcrumed on the clip, an oscillating bar pivoted to the clip and arranged parallel with the lever, a pounder-receiving clamp connected with the bar and with the lever, and a spring for raising the clamp, the lever and the bar, substantially as described.

In testimony that I claim the foregoing as my own I have hereto affixed my signature in the presence of two witnesses.

LEONARD B. BROOKS.
